UNITED STATES PATENT OFFICE

2,119,394

ELECTRIC CABLE

Edward H. Lewis, Union, N. J., and Clifford O. Hull, Stratford, Conn., assignors to General Electric Company, a corporation of New York

Application December 18, 1934, Serial No. 758,012

2 Claims. (Cl. 173—264)

Our invention relates to an electric cable and more particularly to a cable with an overall fibrous braid which will not fray back from the end of the cable.

5 An object of our invention is to provide an improved electric cable in which the outer covering of braid will not become loose and fray back from the end while the cable is in use.

What we consider to be novel and our invention will be better understood by reference to the following specification and appended claims when considered in connection with the accompanying drawing in which the single figure is a side elevation of our improved cable showing the 15 layers of insulation. In cable provided with an overall rubber jacket covered with a fibrous braid difficulty has been experienced due to the fact that the rubber jacket has a smooth exterior surface over which the braided covering is formed. The braided covering at its free end moves freely over the surface of the rubber and is loosened in use and in the course of time the braided covering begins to fray back from the end. To prevent the loosening of the braided 20 covering when it is applied over a rubber jacket, we have provided a plurality of closely arranged ribs on the surface of the rubber jacket which presents a high friction surface to the braid and thus prevents the loosening and fraying back of 25 the braid.

In the drawing, 10 and 11 indicate two stranded conductors. Over the conductors 10 and 11 cotton coverings 12 and 13 are provided which are formed by cotton strands laid longitudinally 30 around the conductors. It may be found desirable to form the cotton coverings 12 and 13 by a braid or winding. Over the cotton coverings 12 and 13 layers of rubber insulation 14 and 15 are provided. Over the combined conductors and 35 insulation an overall rubber jacket 16 is provided with a longitudinal ribbed surface. Over the

rubber jacket 16 a fibrous braid 17 is formed. Due to the ribbed surface on the jacket 16 the braid 17 tightly engages the jacket 16 and does not become loosened with use and so will not fray back from its free end. It may also be 5 found desirable where a single conductor with a rubber jacket is covered with a braid to form the surface of the jacket with ribs to prevent loosening of the braid from the single conductor and its insulation. It is believed that longitudinal ribs will more efficiently prevent the loosening of the braid but it may be found satisfactory in some cases to use ribbed surfaces which extend spirally over the jacket or in any other irregular form.

10 From the foregoing it may be seen that an improved cable is provided with a rubber jacket covered by a braid which will not become loosened with the use of the cable.

15 What we claim as new and desire to secure by 20 Letters Patent of the United States is:

1. An electric cable comprising a conductor, a rubber covering over the conductor having a plurality of small continuous ribs extending throughout its length and which are closely arranged, and a fibrous covering braided tightly 25 over the rubber covering whereby the ribs prevent the ready loosening and fraying back of the braid.

2. An electric cable comprising a plurality of 30 conductors, an insulating covering over each conductor, a rubber jacket over the combined conductors having a plurality of small continuous longitudinal ribs extending throughout its length and which are closely arranged, and a fibrous 35 covering braided tightly over the rubber jacket whereby the ribs prevent the ready loosening and fraying back of the braid.

EDWARD H. LEWIS.
